UNITED STATES PATENT OFFICE.

ROBERT F. FORKNER, OF PRINCETON, WEST VIRGINIA, ASSIGNOR OF ONE-THIRD TO
JOHN B. THOMAS, OF PRINCETON, WEST VIRGINIA.

GASOLENE-ENGINE SYSTEM.

1,300,714.

Specification of Letters Patent. Patented Apr. 15, 1919.

Application filed August 30, 1918. Serial No. 252,110.

To all whom it may concern:

Be it known that I, ROBERT F. FORKNER, a citizen of the United States, residing at Princeton, in the county of Mercer and State 5 of West Virginia, have invented a new and useful Gasolene-Engine System, of which the following is a specification.

It is the object of this invention to provide novel means for supplying fuel vapor 10 to an internal combustion engine, in addition to the regular supply; to provide means whereby water vapor may be directed into the engine to aid in removing carbon; to provide means whereby a lubricant may be 15 supplied to the engine; and to provide means whereby a carbon remover may be delivered to the engine. The invention aims, further, to provide means whereby the various instrumentalities above mentioned may be operated and controlled.

I do not bind myself to the particular arrangement of parts shown in the drawings and hereinafter described, it being clear that, prompted by his skill, a mechanic may 25 make changes, within the scope of what is claimed, without departing from the spirit of the invention.

In the drawings:—Figure 1 is a diagram showing a device constructed in accordance 30 with the invention; Fig. 2 is a section through the tank; Fig. 3 is a sectional detail showing a part of the valve-operating means; and Fig. 4 is a sectional detail showing one of the valves.

The numeral 1 marks the dash board of an automobile. The intake manifold is shown at 2 and the carbureter at 4, the numeral 3 designating a connection between the carbureter and the manifold, and referred to hereinafter as a fuel outlet for the carbureter. The fuel supply pipe for the carbureter 4 is shown at 5. The numeral 6 designates part of the exhaust pipe, which has an enlarged chamber 7.

A tank 8 is supported in any desired way and is divided into compartments 9, 10, 11 and 12. The compartment 9 contains a lubricant, such as cylinder oil. Water is placed in the compartment 10. The compartment 11 holds the fuel, ordinarily gasolene. A mixture of graphite grease and carbon remover is disposed in the compartment 12. The compartments 9, 10, 11 and 12 have sloping bottoms 14 leading to connections 15 wherewith drain cocks 16 are as-

sembled. The compartments 10 and 11 have top connections 17. The compartments 9 and 12 are supplied with top filling plugs 18, the compartments 10 and 11 having side filling plugs 19. The plugs 19, being located in the sides of the compartments 10 and 11, prevent the compartment 10 from being filled completely with water, the same observation being true with respect to the fuel in the compartment 11. All of the compartments are supplied with gage glasses 20 of any approved kind.

One end of an air pipe 21 is mounted in the dash board 1 and carries an intake funnel 22 controlled by a valve 23. The pipe 21 is extended at 24 into the chamber 7 of the exhaust pipe 6 and is formed into a coil 25 within the chamber. From the coil 25, the pipe 21 extends as shown at 26 to the compartment 11 and passes upwardly into the 75 compartment in the form of a coil 27 having a depending funnel-shaped end 28 disposed above the level of the fuel in the compartment. A pipe 29 leads from the top of the compartment 11 to the fuel outlet 3 of 80 the carbureter 4.

One end of a pipe 30, which is an air pipe, is mounted in the dash board 1 and has a funnel-shaped intake 31 controlled by a valve 32. The pipe 30 is extended at 33 to 85 the chamber 7, formed into a coil 34, extended at 35 to the compartment 10, fashioned into a coil 36 within the compartment 10, and terminating in a depending end 37 located above the level of the water in the 90 compartment. A pipe 38 leads from the top of the compartment 10 to the fuel outlet 3 for the carbureter 4. The air passing through the pipes 21 and 30 is heated in the chamber 7 and, in order that the air may 95 not lose its heat, the parts 35 and 26 of the air pipes are jacketed throughout their lengths, a part of the jacketing being denoted by the numeral 58 in Fig. 1.

A pipe 39 extends along the tank 8 and is 100 connected at one end to the fuel supply 5 of the carbureter 4. The pipe 39 has a branch 40 leading to the connection 15 of the compartment 9, a branch 41 connecting the pipe 39 with the compartment 11, and a branch 105 42 connecting the pipe 39 with the compartment 12. Sight feed devices 43 are interposed in the branches 40, 41 and 42, to regulate the flow from the compartments 9, 11 and 12, through the respective branches. 110

Casings 44 are interposed in the branches 40, 41 and 42, and in the casings, valves 45 are journaled. The valves may be operated in any desired way, for instance, by connections 46 pivoted to bell cranks 47, fulcrumed at 48, and connected at 49 to operating members 50 slideable in the dash board 1 and in casings 51 on the dash board, the casings inclosing spring-pressed latches 52 coöperating with seats 53 in the members 50.

5 A valve 54 is interposed in the pipe 39 between the carbureter 4 and the branch 42 and is actuated by a connection 55 connected with a bell crank 56 under the control of an operating member 57 of the kind above alluded to. It will be obvious that by sliding, for instance, the operating member 50 endwise, the bell crank 56 will operate the valve 54 by way of the connection 55. The 10 valves 44 are controlled in a similar way, and in describing the operation of the valves, the particular means for working them will be dismissed, as being thoroughly understood by those skilled in the art.

25 The valve 23 may be opened, thus admitting air into the end 22 of the pipe 21. The suction of the engine draws the air through the coil 25, wherein the air is heated by the exhaust, the heated air traversing the 30 coil 27 and heating the fuel in the compartment 11. The heated air ultimately is discharged downwardly from the end 28 of the pipe 21 on the fuel, a mixture of fuel vapor and heated air entering the fuel outlet 3 of the 35 manifold 4 by way of the pipe 29. The mixture thus is enriched, with consequences, which are understood by those accustomed to the management of internal combustion engines. If it is desired to project the liquid 40 gasoline directly into the fuel supply 5 of the carbureter 4, then the valve 44 in the branch 41 may be opened, the sight feed regulator in the branch 41 having been set and adjusted, so that the flow through the branch 45 41 will be controlled to the desired extent.

In a similar way, air passing into the pipe 30 when the valve 32 is opened, is heated in the coil 34 and heats the water in the compartment 10, the hot air being discharged 50 from the end 37 of the pipe 30 on top of the water. The water vapor is sucked through the pipe 38 into the fuel outlet 3 of the carbureter 4 and aids in removing the carbon from the engine cylinders.

55 The lubricant in the compartment 8, being regulated by the sight feed device 43 in the branch 40, is admitted by the valve 44 in the said branch, into the pipe 39, and passes from thence into the fuel supply 5, 60 the lubricant ultimately finding its way into the cylinders, to grease the pistons, and particularly the top rings thereof.

The carbon remover in the compartment 12, regulated by the sight feed device 44 in 65 the branch 42, passes, when the valve 44 in

said branch is opened, into the pipe 39, the fuel supply 5, and ultimately into the engine cylinders, to do the work which the name "carbon remover" implies.

It will be observed that the flow from the compartments 9, 11 and 12 may be regulated individually by the valves 44, and the combined flow proceeding from the pipe 39 into the fuel supply pipe 5 may be regulated by means of the valve 54. Noting that the valves 32 and 23 are individually operable, and noting the pipes 29 and 38, as well as the valves 44 in the branches 40, 41 and 42, it will be understood that a wide variety of combinations may be made up, so far as the materials delivered into the engine cylinders are concerned.

The device forming the subject matter of this application serves to increase the speed of an internal combustion engine, and aids in the running of the engine at slow speed in high gear on automobiles. Further, the motor will be kept cool at all times and will run on a comparatively lean spark. If the motor is used in connection with dry cells or a storage battery, an appreciable saving in current will be noted.

The chamber 7 is in addition to the regular muffler and serves to silence the exhaust and to relieve the compression on the up-stroke of the piston. The cylinder oil derived from the compartment 9 lubricates the upper end of the piston. The water vapor proceeding from the compartment 10 softens the carbon and aids in carrying out the carbon through the exhaust pipe, after the carbon has been softened by the removing compound supplied from the compartment 12. The graphite from the compartment 12 keeps the valves clean and the bearings smooth. The gas vapor produced effects a more perfect combustion and a more perfect explosion than is possible without the use of the device hereinbefore described, and a saving of fuel results. It is within the power of the operator to use one of the compartments at a time, or to use all of them together. When the valve 44 in the branch 41 is opened, a supply of liquid gasoline may be directed into the pipe 5 in front of the carbureter 4, and, consequently, the compartment 11 has the functions of a reserve supply tank.

I claim:

1. In a device of the class described, a motor vehicle frame; a carbureter having a fuel outlet; an exhaust; a compartment; a conduit leading from the top of the compartment to the outlet; an air pipe having one of its ends located on the frame and having the other of its ends open within the compartment adjacent the top thereof, the pipe coöperating with the exhaust to be heated thereby, and passing through the compartment; a valve controlling the first

specified end of the air pipe and accessible to an operator of the vehicle; a fuel supply for the carbureter; a connection between the lower portion of the compartment and the 5 fuel supply; and means for controlling the passage of the contents of the compartment through the connection.

2. In a device of the class described, a carbureter having a fuel outlet; an exhaust; a 10 compartment; a conduit leading from the top of the compartment to the outlet; an air pipe coöperating with the exhaust to be heated thereby, one end of the pipe entering the compartment and being open adjacent 15 the top of the compartment; a valve controlling the other end of the pipe; a fuel supply for the carbureter; a connection between the lower portion of the compartment and the fuel supply; mechanism for regulat- 20 ing the flow through the connection; and means independent of said mechanism for stopping the flow through the connection.

3. In a device of the class described, a carbureter having a fuel outlet; an exhaust; a 25 first compartment; a second compartment; a conduit leading from the top of the first compartment to the outlet; an air pipe coöperating with the exhaust to be heated thereby, one end of the pipe passing into the first 30 compartment and having one of its ends open adjacent the top of the first compartment; a valve controlling the other end of said pipe; a fuel supply for the carbureter; means for connecting the lower portions of 35 the first and second compartments with the fuel supply; and independent controlling devices in said means and under the control of an operator.

4. In a device of the class described, a 40 carbureter having a fuel outlet; an exhaust; a first compartment; a second compartment; a conduit leading from the top of the first compartment to the outlet; an air pipe coöperating with the exhaust to be heated 45 thereby, one end of the pipe passing into the first compartment and having one of its ends open adjacent the top of the first compartment; a valve controlling the other end of said pipe; a fuel supply for the carbureter; a second pipe leading to the fuel supply and having branches communicating 50

with the lower portions of the compartments; controlling means in the branches; and a valve in the second pipe, between the carbureter and that branch which is nearest 55 to the carbureter.

5. In a device of the class described, a carbureter having a fuel outlet and a fuel inlet; four compartments; a pipe connected with the fuel inlet and having branches 60 leading to the lower portions of three of the compartments; controlling means in the branches; a valve in the pipe between the carbureter and that branch which is next to the carbureter; conduits leading from the 65 upper portions of one of the three compartments and from the fourth compartment to the fuel outlet; an exhaust; a pair of pipes coöperating with the exhaust to be heated thereby, the pipes passing into the fourth 70 compartment and into said one of the three compartments and having open ends disposed adjacent the tops of said compartments; and valves controlling the other ends of the last specified pipes. 75

6. In a device of the class described, a carbureter having a fuel outlet and a fuel inlet; four compartments; a pipe connected with the fuel inlet and having branches leading to the lower portions of three of the 80 compartments; means in the branches for regulating the flow therethrough; means in the branches for shutting off the flow therethrough; conduits leading from the upper portions of one of the three compartments 85 and from the fourth compartment to the fuel outlet; an exhaust; a pair of pipes coöperating with the exhaust to be heated thereby, the pipes passing into the fourth compartment and into said one of the three 90 compartments and having open ends disposed adjacent the tops of said compartments; and valves controlling the other ends of the last specified pipes.

In testimony that I claim the foregoing 95 as my own, I have hereto affixed my signature in the presence of two witnesses.

ROBERT F. FORKNER.
